UNITED STATES PATENT OFFICE.

CHARLES G. TREFETHEN, OF PROVIDENCE, RHODE ISLAND, ASSIGNOR TO ATLAS MACHINE
TOOL COMPANY, A CORPORATION OF MAINE.

MICROMETER-FEED FOR GRINDING-MACHINES.

No. 915,123.

Specification of Letters Patent. Patented March 16, 1909.

Application filed March 2, 1908. Serial No. 418,786.

To all whom it may concern:

Be it known that I, CHARLES G. TREFETHEN, a citizen of the United States, residing at Providence, in the county of Providence and State of Rhode Island, have invented certain new and useful Improvements in Micrometer-Feeds for Grinding-Machines, of which the following is a specification.

My invention relates to micrometric feeds for grinding machines whereby the grinding wheel and slide are advanced toward the article to be ground; and is primarily directed to the actuating mechanism for the reciprocating pawl, and to the construction and operation of the carrier.

The objects of my invention are those commonly sought in this class of structures; but more particularly to provide means for varying the intensity or depth of the feed or advance of the grinding wheel at each stroke of the reciprocating platen or bed plate; to lessen the wear on the disk teeth; and to make the action of the reciprocating pawl upon the disk certain and positive.

25 A further object is to provide a simple, accurate, and effective device for manually operating the micrometric feed. Also to improve the means for automatically advancing the toothed disk, and the means for adjusting the advancing means.

In the drawings which constitute a part of these specifications, Figure 1 is a front elevation of a portion of the frame of a grinding machine equipped with my novel feed; a portion of the band wheel being broken away. Fig. 2, a plan view of the same. Fig. 3, a section on line *x-x* of Fig. 1. Fig. 4, a rear elevation of the carrier. Fig. 5, a detail view of the pawl, and Fig. 6, a section on line *y-y* of Fig. 5.

Like reference characters indicate like parts throughout the views.

In the drawings, 1 is the frame, 2 the platen, 3 the adjustable stops upon the platen, 4 the screw spindle, 4' the spindle bearing, 5 the hand wheel of the spindle, 6 the disk fixed to the spindle and provided with ratchet teeth, 7, 8 the rock shaft, and 9 the operating or rock lever, and 10 the lever handle, of an ordinary grinding machine. The grinding wheel slide and its connection with the spindle, 4, are of the usual construction.

Pivoted at one end upon a stud, 11, in the frame below the lever, 9, is a horizontal lever, 12, provided intermediate its length with two interspaced threaded openings, 13 and 14, in which are mounted vertical adjusting screws, 15 and 16, respectively. Above the lever, 12, is a stud, 17, upon which is a hub, 18, provided with three radially disposed legs, 19, 20 and 21, equidistant from each other. A link, 22, connects the lower end of the lever, 9, with the vertical leg, 19; and the legs, 20 and 21, normally contact with the flat upper surfaces of the screws, 15 and 16, respectively. A link, 24, connects the free end of the lever, 12, with the intermediate portion of an arm, 25, pivoted to the screw spindle, 4, in the rear of the disk, 6. Pivoted to a pin, 26, in the end of the arm, 25, is a pawl, 27, adapted to engage the ratchet teeth, 7. To facilitate engagement and disengagement of the pawl, cavities 28 and 29 are provided in the pawl face adapted to receive the curved end of a pin, 30, slidably mounted in the arm, 25, and pressed by a spring, 31, which is retained by a screw, 32, as shown in Fig. 6. A helical spring, 34, has one end fixed to a pin, 34', in the machine frame above the lever, 12, and its other end connected to the latter, whereby the screws, 15 and 16, are normally pressed against the arms, 20 and 21.

The mechanism employed in actuating the disk, 6, when the latter is operated by power has been described. The means for manually operating the disk comprises a carrier, 35, fixed to or integral with the free end of an arm, 36, which is pivotally mounted upon the spindle, 4, adjacent the front face of the disk, 6. The carriage overhangs the periphery of the disk, and is, with the arm, 36, independent of the latter. A shield, 37, is fixed to one end of the carrier. A hand lever, 38, is pivoted intermediate its length upon a pin, 39, in the carrier. A spring arm, 40, is held against the under face of the lever by a rivet, 40', passing through the outer ends of each. The inner end of the arm, 40, terminates in a downwardly inclined finger, 41. An adjusting screw, 43, is mounted in the lever, 38, and presses downwardly against the arm, 40, to force the finger, 41, into engagement with the teeth of the disk, 6. The inner end of the rod is downwardly pressed by a spring, 44, fixed in the carrier. The carrier is also provided with a vertical slot, 46, adapted to re-

ceive hooked end, 47, of a lock bar, 48, pivoted to the frame, 1. An opening, 49, in the carrier arm, 36, contains a friction plate, 50, spring, 51, and screws, 52, adapted to form, 5 when desired, an adjustable frictional engagement with the front of the disk to prevent over-rotation of the latter.

The operation of the mechanism is as follows: The dogs, 3, upon the reciprocating platen vibrate the lever, 9, which through the link, 22, alternately elevates and lowers the arms, 20, 21, thereby vibrating the lever, 12, and, through link, 24, the arm, 25, whereby the pawl, 27, moves the disk, 6, and its screw spindle one or more teeth. Thus intermittent rotary motion is imparted to the disk and spindle. By elevating or depressing the screws, 15 and 16, relatively to each other, the pawl arm, 25, and disk, 6, will both be advanced different distances at each successive reciprocation of the platen, 2, whereby a fine and coarse feed will be alternately afforded. During the operation of the hand feed, the pawl, 27, is swung out of the path of the teeth, 7, whereby the pin, 30, is forced out of the cavity, 28, and enters the cavity, 29, thus maintaining the pawl out of the path of the ratchet teeth. The hand feed is operated by initially turning the screw, 43, to depress the finger, 41, into the path of the disk teeth, and then alternately elevating and depressing the outer end of the hand lever. It is often desirable to lock the carrier, 35, or arm, 36, against movement relatively to the ratchet disk. This end is attained by dropping the hooked bar, 48, into the slot, 46, of the carrier. Over-rotation of the disk, 6, may be prevented by pressing the friction plate, 50, against the disk by means of the spring, 51, and screw, 52. By mounting the arm, 25, upon the spindle or concentric therewith a more positive action upon the disk, 6, is secured, and without injury to the teeth, 7, by the pawl, 27. It will be observed that the adjustment of the screws, 13 and 14, not only governs the degree of rotation of the toothed disk, but regulates also the relative difference in the advance of the disk in each successive vibration.

50 What I claim is,

1. In a micrometric feed for a grinding machine the combination with the screw spindle and disk, of means for advancing the disk a different distance at each successive impulse.

60 2. In a micrometric feed for a grinding machine the combination with the screw spindle and disk provided with ratchet teeth, of a pawl engaging the ratchet teeth, and means for impelling the pawl a different distance at each successive impulse.

65 3. In a micrometric feed for a grinding machine the combination with the screw spindle and disk provided with ratchet teeth, of an arm loosely mounted upon the spindle,

a pawl upon the arm and engaging the ratchet teeth, and means for reciprocating the arm.

4. In a micrometric feed for a grinding machine the combination with the screw 70 spindle and disk provided with ratchet teeth, of an arm loosely mounted upon the spindle, a pawl upon the arm and engaging the ratchet teeth, and means for reciprocating the arm a varying distance. 75

5. In a micrometric feed for a grinding machine the combination with the screw spindle, toothed disk, and operating lever, of an arm upon the spindle, a pawl on the arm engaging the disk, a second lever, a link, 80 connecting the second lever to the arm, and means actuated by the operating lever for vibrating the second lever.

6. In a micrometric feed for a grinding machine the combination with the screw 85 spindle, toothed disk, and operating lever, of an arm pivoted upon the spindle, a pawl upon the arm engaging the disk, a horizontal lever, a link connecting the horizontal lever to the arm, vertically adjustable screws in 90 the horizontal lever, a rocking member above the horizontal lever, arms upon the rocking member adapted to contact with the screws, and a link connecting the rocking member to the operating lever. 95

7. In a micrometric feed for a grinding machine the combination with the screw spindle, and toothed disk, of a pawl arm pivotally mounted upon the spindle, a pawl upon the arm adapted to engage the disk 100 and provided with interspaced cavities, a 105 slideable pin in the arm adapted to enter the cavities, and means for vibrating the pawl arm.

8. In a micrometric feed for a grinding machine the combination with the screw spindle and disk provided with ratchet teeth, of an arm pivotally mounted upon the spindle, a carrier upon the arm independent 110 of the disk, and pivotal means in the carrier adapted to engage a ratchet tooth and advance the disk. 105

9. In a micrometric feed for a grinding machine the combination with the screw spindle and disk provided with ratchet teeth, 115 of an arm pivotally mounted upon the spindle, a carrier upon the arm, a hand lever pivoted to the carrier and a finger upon the arm adapted to engage the ratchet teeth.

10. In a micrometric feed for a grinding machine the combination with the screw spindle and disk provided with ratchet teeth, of an arm pivotally mounted upon the spindle, a carrier upon the arm, a hand lever pivoted to the carrier, a spring arm upon the hand lever, a finger upon the spring arm adapted to engage the ratchet teeth, and an adjusting screw in the hand lever adapted to contact with the spring arm. 125

11. In a micrometric feed for a grinding 130

- machine the combination with the screw spindle and disk provided with ratchet teeth, of an arm pivoted to the spindle, a carrier upon the arm, a hand lever pivoted intermediate its length to the carrier, an arm upon the hand lever, a finger upon the arm adapted to engage the ratchet teeth and yielding means in the carrier for depressing one end of the hand lever.
12. In a micrometric feed for a grinding machine the combination with the screw spindle, ratchet disk, and means for intermittently rotating the disk of yielding means contacting with the face of the disk for preventing over-rotation.
13. In a micrometric feed for a grinding machine the combination with the screw spindle, ratchet disk and means for intermittently rotating the disk, of an arm loosely mounted upon the spindle, means for locking the arm against movement, a friction plate in the arm adjacent the disk, and yielding means in the arm for pressing the plate into frictional contact with the face of the disk.
14. The combination with the frame, screw spindle, ratchet disk, and disk operating mechanism of a grinding machine, of an arm loosely mounted upon the spindle, frictional means upon the arm contacting with the disk, and means upon the frame for locking the arm against movement.
15. The combination with the frame, screw spindle, and ratchet disk of a grinding machine, of a carrier arm loosely pivoted upon the screw spindle, a carrier upon the arm, a hand lever in the carrier, an arm on the lever, a finger on the arm adapted to engage the ratchet disk, and a lock bar pivoted to frame and engaging the carrier.
16. In a micrometric feed for a grinding machine the combination with a screw spindle, toothed disk, and operating lever, of an arm pivoted to the spindle, a pawl upon the arm engaging the disk, a second lever, a link connecting the second lever with the arm; a rocking member above the second lever, a link connecting the rocking member to the operating lever, and adjusting means in the second lever contacting with the rocking member.

In testimony whereof I have affixed my signature in presence of two witnesses.
